UNITED STATES PATENT OFFICE.

GEORGE SMITH, OF LOUISIANA, MISSOURI.

FIRE-ESCAPE LADDER.

1,258,487.

Specification of Letters Patent. Patented Mar. 5, 1918.

Application filed June 4, 1917. Serial No. 172,811.

To all whom it may concern:

Be it known that I, GEORGE SMITH, a citizen of the United States, residing at Louisiana, in the county of Pike, State of Missouri, have invented certain new and useful Improvements in Fire-Escape Ladders; and I do hereby declare the following to be a full, clear, and exact description of the invention, such as will enable others skilled in the art to which it appertains to make and use the same.

This invention relates to safety fire appliances and is directed more particularly to a fire escape ladder.

An object of the present invention resides in the provision of a ladder of a type to permit of its use for general household purposes and at the same time to embody in its construction a mechanism through the medium of which it may be utilized as a fire escape by which the occupants of a building may descend with safety to the street below.

With the above and other objects of similar nature in view, the invention consists in the construction, combination and arrangement of parts, set forth in and falling within the scope of the appended claim.

In the drawing:—

Figure 1 is a side elevation of the device in use as a ladder.

Fig. 2 is a front view thereof.

Fig. 3 is a section taken on the line 3—3 of Fig. 1.

Fig. 4 is a front elevation showing the device in use as a fire escape; and,

Fig. 5 is a vertical section therethrough showing the brakes applied.

Referring now more particularly to the accompanying drawing there is shown a ladder including the front and rear sections, 10 and 11 respectively, that are pivotally connected at their upper ends as shown at 12 and are connected intermediate their ends by means of the usual break joint brace 13.

Journaled between the side rails 14 of the rear section 11 is a drum 15 enlarged at its ends as shown at 16. Encircling each of the enlarged portions 16 is a brake band 17 the ends of which are provided with transverse bearing eyes 18. To actuate the bands 17 to frictionally engage the enlarged portion 16 of the drum 15 there is provided a substantially U-shaped operating member 19, the legs of which are constructed as shown at

20 to pass through the bearing eyes 18 of 55 the bands, and have their terminals journally engaged in the corresponding side rails 14 whereby to operatively support said member. Pivoted as at 21 to an upper round of the rear section 11 is a platform 22 which, 60 when the appliance is employed as a ladder, assumes the position illustrated in Fig. 1. Wound upon the drum 15 inwardly of its ends 16, are a pair of cables 23 carrying at their free ends hooks 24, while provided on 65 the rails 14 of the rear section 11 are guides 25 through which the cables are slidably passed.

The use of the device as a ladder, it is thought will be readily apparent from the 70 drawing and needs no further explanation. However when employing the same as a fire escape it is inverted as shown in Figs. 4 and 5, and the hooks 24 of the cables 23 engaged with a window sill or other suitable 75 support in the building in which the fire occurs. The platform 22 is then swung to the position shown in Fig. 5 and the ladder passed outwardly through the window. When so disposed, one or more 80 occupants of the building will step upon the platform 22 and will be lowered with the ladder to the ground, the brake bands 17 being actuated through the medium of the operating member 19 to regulate the speed 85 of the descent and the cables 23 unwinding from the drum 15 as will be evident. There is thus provided a structure, which under normal conditions, may be effectively employed as a ladder, and which in case of 90 fire or other emergency may be quickly and conveniently converted into a device, through the instrumentality of which, the occupants of a building may be lowered from the upper floors with ease and safety. 95

What I claim is:—

In combination a ladder including pivotally connected front and rear sections, a platform carried by the rear section for positioning horizontally between the sections, a drum journaled in the rear section, suspending cables wound upon the drum, and braking means associated with the drum for regulating the speed with which the cables are unwound from the latter. 100

In testimony whereof, I affix my signature.

REV. GEORGE SMITH.
